UNITED STATES PATENT OFFICE.

ERNEST J. HAMM, OF JERSEY CITY, NEW JERSEY.

WINDOW-SHADE.

SPECIFICATION forming part of Letters Patent No. 320,245, dated June 16, 1885.

Application filed January 29, 1885. (No model.)

To all whom it may concern:

Be it known that I, ERNEST J. HAMM, a citizen of the United States, residing at Jersey City, in the county of Hudson and State 5 of New Jersey, have invented new and useful Improvements in Window-Shades, of which the following is a specification.

My invention consists in the combination, with a shade-roller and the stiffening-strip, of 10 a paper, muslin, or linen shade, made of one piece and having a portion thereof which overlaps and falls below the stiffening-strip, said portion being provided with perforations and 15 fringe or scallops in imitation of lace, and also in the combination, with a shade-roller and the stiffening-strip, of a paper, muslin, or linen shade which is made of one piece, a loop formed at a distance from the lower end for the reception of the stiffening-strip, the part below the 20 loop being provided with perforations, and fringe or scallops in imitation of lace.

In the accompanying drawings, Figure 1 is a transverse section of a portion of my improved shade. Fig. 2 is a front elevation of 25 the same.

Similar letters indicate corresponding parts. In the drawings, the letter A designates a portion of the shade, which is made either of paper, linen, or other similar material, and 30 which is secured at its upper end to a shade-roller of any construction. At the lower end of the shade, and near the end of the same, a loop, a, for the reception of the stiffening-strip B, is formed by turning up the shade and 35 stitching the part turned up to the body of the shade along the line b b, Fig. 2, whereby an overhanging part, C, remains below the loop a, which part C overlaps and falls below the stiffening-strip B. This overhanging part 40 C, as shown in the drawings, Fig. 2, is provided with perforations, the shape and general design of which may be varied indefinitely, and it is also provided on its end with fringe or scallops cut into the material, the result of

the perforations, fringe, or scallops being that 45 this overhanging portion presents the appearance of lace. The various designs on this part of the shade can be cut out by steel dies in the ordinary manner.

As described, this shade is made entirely of 50 one piece, and, when manufactured from paper, muslin, or linen, can be produced rapidly and at a comparatively low price, while at the same time it has the appearance of curtains trimmed with lace. 5

I am aware that window-curtains, lambrequins, &c., were made from paper perforated and scalloped in imitation of lace; but these articles were merely attached to the window or similar place, and were not in connection 6 with a shade-roller and a stiffening-strip.

What I claim as new, and desire to secure by Letters Patent, is—

1. The combination, substantially as hereinbefore described, with a shade-roller and 6 the stiffening-strip, of a paper, muslin, or linen shade made of one piece, and having a portion which overlaps and falls below the stiffening-strip, said portion being provided with perforations and fringe or scallops in 7 imitation of lace.

2. The combination, substantially as hereinbefore described, with a shade-roller and the stiffening-strip, of a paper, muslin, or linen shade which is made of one piece, the 7 loop a formed at a distance from its lower end for the reception of the stiffening-strip, the part below the loop being provided with perforations, fringe, or scallops in imitation of lace. 8

In testimony whereof I have hereunto set my hand and seal in the presence of two subscribing witnesses.

ERNEST J. HAMM. [L. S.]
